UNITED STATES PATENT OFFICE.

FRANCIS J. HAGE, SR., OF GOLDSBORO, NORTH CAROLINA.

HERNIAL TRUSS.

SPECIFICATION forming part of Letters Patent No. 671,999, dated April 16, 1901.

Application filed December 31, 1900. Serial No. 41,717. (No model.)

To all whom it may concern:

Be it known that I, FRANCIS J. HAGE, Sr., a citizen of the United States, residing at Goldsboro, in the county of Wayne and State of 5 North Carolina, have invented a new and useful Truss, of which the following is a specification.

This invention relates to improvements in trusses; and the object is to provide a simple, 10 cheap, and comfortable truss for successfully arresting either single or double hernia, which may be readily adjusted, and which will cause absolutely no inconvenience, pain, or annoyance to the wearer.

With the above object in view the invention 15 consists in the novel features of construction hereinafter fully described, particularly pointed out in the claims, and clearly illustrated by the accompanying drawings, in 20 which—

Figure 1 is a front view of my truss in position upon the body of a wearer; Fig. 2, a rear view of the same; Fig. 3, a view of the truss detached, and Fig. 4 a sectional view 25 through the bandage of the truss.

Referring now more particularly to the drawings, A designates the front or bandage portion of my improved truss, which is of such size and shape as to cover the lower portion 30 of the abdomen. This bandage or front portion A is elongated at its upper edge and at its respective ends to form oppositely-extending waistband-sections B B, designed to be placed about the waist of the wearer, crossed 35 at the back, and brought around the body again to the front thereof, as illustrated in Figs. 1 and 2. Bandage A and sections B B are formed of two pieces of material of the same outline, placed flatly in contact, and secured 40 by stitching the same along the edges thereof. A piece of hairecloth or similar material C is placed between the two pieces of material comprising the bandage for the purpose of stiffening the same and giving to it a 45 certain amount of elasticity.

Secured to the ends of waistband-sections B B are straps D D', strap D being considerably longer than strap D', and each of said straps is provided at its free end with a buttonhole E.

Waistband-sections B B are provided with buttons F F, which when the truss is in po-

sition upon the wearer are disposed at the back portion of the body.

Bandage A is formed at its lower edge with a recess G to fit around the upper portion of the penis and with two depending portions H H extending downwardly, one on each side of the penis, and passing beneath the crotch of the wearer. The bandage A, waistband- 60 sections B B, and depending crotch portions H H are all formed integrally, as will be seen from the drawings.

Secured to the ends of crotch portions H H are straps I I, which pass beneath the crotch 65 and are brought upwardly at the back of the wearer and at their ends attached to buttons F F of the waistband-sections B B, being formed with buttonholes J J for this purpose.

The truss, as illustrated in Figs. 1 and 2, is 70 applied to a hernia on the right side of the body, and the longer strap D is carried around the right thigh and secured at its end to the bandage A by having its buttonhole E receive a button K, carried by the lower portion of 75 the bandage. Strap D' is secured at its end to a button L, also carried by the bandage.

To adapt the truss for a hernia upon the left side of the body, the former is simply reversed and placed with what is its inner side 80 in Fig. 1 out, so as to bring the longer strap D on the left side of the body.

A truss constructed as above set forth is exceedingly comfortable to the wearer, as there is no extra pressure or friction, but sufficient 85 even pressure to thoroughly arrest the hernia. It is also simple in construction, capable of quick and convenient adjustment, and when once adjusted needs no further adjustment and may be worn both during the day and 90 night and when soiled washed to cleanse the same without injury thereto. Besides, it is light and elastic, so as to permit free movement of the body, and may be manufactured and sold at a very small price, so as to be 95 within the reach of all sufferers from hernia.

Having thus fully described my invention, what I claim as new, and desire to secure by Letters Patent, is—

1. A truss comprising a bandage having 100 straps adapted to be passed around the waist to the back and crossed and brought back to the front, fastening means carried by the bandage and the ends of said straps for attach-

- ing the latter to the former, one of said straps being of a sufficient length to pass around the thigh before being attached to the bandage, straps extending from the lower portion of 5 the bandage and adapted to be passed under the crotch and upward at the back of the wearer, and fastening means carried by the waist-straps and the ends of the crotch-straps whereby the latter may be attached to the 10 former, substantially as described.
2. A truss comprising a front portion or bandage of a size and shape adapted to fit the lower portion of the abdomen, waistband-sections carried by said bandage and of a length 15 to be passed around the waist to the back and crossed and returned to the front of the body,

straps secured to the ends of said waistband-sections, fastening means carried by said bandage and straps whereby the ends of the latter may be attached to the former, one of 20 said straps being adapted to be passed around the thigh before attachment to the bandage, crotch portions depending from the bandage, straps secured to said crotch portions, and fastening means carried by the ends of the 25 straps and the waistband-sections whereby the latter may be attached to the former, substantially as described.
